(57) **CLAIM**

We claim the ornamental design for a toothbrush with releasable, replaceable head, as shown and described.

DESCRIPTION

FIG. 1 is a perspective view of a toothbrush with releasable, replaceable head showing our new design;

FIG. 2 is a side elevational view thereof, the elevational view of the opposing side being a mirror image thereof;

FIG. 3 is an end elevational view thereof;

FIG. 4 is an elevational view of the opposing end thereof;

FIG. 5 is a top plan view thereof; and,

FIG. 6 is a bottom plan view thereof.

The various views show a head released from a handle thereof.

The individual strands which make up the densely packed tufts are partially shown for ease of illustration.
